UNITED STATES PATENT OFFICE.

HERMAN F. RICHTER, OF LOS ANGELES, CALIFORNIA, ASSIGNOR TO HYNES SHADE GUIDE COMPANY, OF LOS ANGELES, CALIFORNIA, A CORPORATION OF CALIFORNIA.

SHADE-CONTROLLER.

1,104,221.

Specification of Letters Patent. Patented July 21, 1914.

Application filed July 14, 1913. Serial No. 778,856.

To all whom it may concern:

Be it known that I, HERMAN F. RICHTER, a citizen of the United States, residing at Pasadena, in the county of Los Angeles and 5 State of California, have invented a new and useful Shade-Controller, of which the following is a specification.

This invention relates to a device adapted to be used for preventing a shade from being unrolled too far and accidentally torn from the shade roller, and for preventing the shade roller from winding up the shade any farther than complete raised position of the shade, thus obviating accidental 10 unwinding of the spring or damage to the shade should the shade slip out of the hand while being adjusted.

Referring to the drawings: Figure 1 is a front elevation of a shade roller and shade 20 equipped with the invention. Fig. 2 is an enlarged front elevation of a corner portion of what is shown in Fig. 1, with part broken away. Fig. 3 is a plan view of what is shown in Fig. 2. Fig. 4 is a view similar 25 to Fig. 3, showing the shade removed from the shade roller and the shade roller turned one quarter from its position in Fig. 3. Fig. 5 is a side elevation of the upper portion partly in section. Fig. 6 is an enlarged 30 section on line x^6-x^6 , Fig. 4. Fig. 7 is a perspective in detail of one of the spring fingers. Fig. 8 is a perspective of the adjustable stop lug.

1 designates the shade roller which is rotatable mounted at each end in brackets 2 35 of the usual or any preferred construction.

3 is the shade secured to the shade roller in any desired manner.

4 designates a spring finger which is 40 shown in detail in Fig. 7 and is formed integral with a base 5, the latter having an out-turned loop 6 through which projects the end of the finger and which acts to guide the finger 4 whereby the projecting end of the finger 45 is retained in its proper position on the shade roll and also limit the outward spring movement of the finger. The base 5 has perforated ears 7 which are bent to conform to the shade roller 1 and which may be 50 secured thereto by screws or tacks, as shown. The other end of the base 5 is perforated at 8 to receive a fastening tack or screw. In the present embodiment, I have shown two of such spring fingers located at one end of

the shade roller in such a manner that the 55 spring finger 4 projects beyond the edge end of the roller, but it should be understood that a greater or less number of spring fingers could be employed if desired. The spring fingers are thin, broad and flat, so 60 that the shade can be rolled over them to spring them in flush with their bases 5 without causing the shade to appreciably bulge and by reason of the wide construction of the spring fingers, there is no tendency to 65 split or tear the shade, as a considerable area of it is covered by the spring finger. This also prevents a tendency to stretch the shade at the edge which is apt to occur if a narrow spring finger is employed. 70

Secured to the bracket 2 is an adjustable stop lug 9, the end of which, as clearly shown in Figs. 4 and 6, lies at some distance from the periphery of the shade roller so that if the spring fingers 4 are sprung down 75 into contact with the shade roller they will freely pass by the stop lug 9 without contacting therewith. The stop lug 9 projects from a plate 10 which is slotted at 12 and is preferably secured in position by a screw 80 13 which screw also serves to retain the bracket 2 in position. This construction permits the stop lug 9 to be adjusted longitudinally with respect to the shade roller, and it should be so adjusted as shown in 85 Fig. 4, that it will lie within the path of movement of the spring fingers when they are extended.

When the shade roller is wound up it springs the fingers 4 down flush with their 90 bases 5 so that while there is at least enough shade wound on the roller to cover the spring fingers, they will be prevented from coming in contact with the stop lug 9, but if the shade be almost entirely unwound 95 enough to uncover the next one or both spring fingers, it will allow one or both spring fingers to spring outward and strike against the stop lug 9, thus preventing the shade from being further unwound, and 100 thereby obviating the shade from being torn off. Thus, the spring fingers should be so arranged that the shade will still be wound partially on the shade roller after the spring fingers are released, which will give sufficient grip on the roller to prevent it from 105 being torn off.

In order to prevent the shade from being

wound up beyond a full open position, I employ two projecting arms 13' which are secured to opposite sides of the lower bar 14, as shown in Figs. 1 and 5 and are adapted to strike against the brackets 2 and limit upward movement of the shade after it has arrived at the top of the window, as indicated in Fig. 1. Thus, if the shade should accidentally escape from the hand, it will fly up to the top, but will not allow the shade roller to further unwind, as the arms 13' will strike brackets 2 and positively prevent such movement.

What I claim is:

- 15 1. In combination with the shade roller and shade secured thereto, a broad plate of sheet metal secured to the shade roller, said plate being slit to form a spring finger, the outer end of the plate being formed as a closed loop bent at right angles to the main portion of the plate and forming a guide for the spring fingers and limiting its outward movement, and a stationary stop lug in the path of movement of said spring finger when the finger is extended.
- 20 2. In combination with a shade roller and shade thereon, a pair of broad thin plates secured to the shade roller near one end thereof, on opposite sides of the shade roller, each broad plate being slit to form a spring tongue, the outer end of the plate being bent at right angles to form a closed loop through which the said tongue projects, and a stationary stop lug adapted to arrest either of

said spring fingers and stop rotation of the 35 spring roller.

3. In combination with a shade roller and shade thereon, a broad thin spring finger secured to the shade roller and adapted to be held against the shade roller when the shade is wound thereon, a stationary stop adjacent the end of the spring finger and in the path of movement thereof when the spring finger is allowed to spring away from the roller, said stationary stop comprising a slotted plate with a lug bent at right angles thereto, and a screw through the slotted plate.

4. In combination with the shade roller and shade secured thereto, a plate of sheet metal secured to the shade roller, a spring finger formed on said plate, a member formed on said plate adapted to guide the projecting end of said finger and to limit the outward movement thereof, a stop adapted to be engaged by the projecting end of said finger when the shade is unwound and the projecting end of the finger is swung outwardly, to arrest the unwinding motion of the shade roller.

In testimony whereof, I have hereunto set my hand at Los Angeles, California this 27 day of June 1913.

HERMAN F. RICHTER.
